ATTORNEY

UNITED STATES PATENT OFFICE.

BURT M. MOORE, OF SAN JOSE, CALIFORNIA, ASSIGNOR OF ONE-HALF TO FLOYD S. MOORE, OF SAN JOSE, CALIFORNIA.

HINGE.

Application filed May 31, 1922. Serial No. 564,846.

To all whom it may concern:

Be it known that I, BURT M. MOORE, a citizen of the United States, and resident of San Jose, in the county of Santa Clara and State of California, have invented certain new and useful Improvements in Hinges, of which the following is a specification.

It is the object of my invention to provide a simple door or gate hinge of few parts 10 easily formed and assembled and provided with an easily replaceable resilient means for normally holding the hinge in a closed position.

In the drawing:—

15 Figure 1 is an outside elevation of my improved hinge.

Figure 2 is an inside elevation of the same.

Figure 3 is a sectional view on 3—3 of Figure 1.

20 Figure 4 is a plan view of a blank for one portion of the hinge after cutting but before shaping.

Referring more particularly to the drawing, 1 indicates one leaf of the hinge attachable to a door casing and having one edge turned outwardly at substantially right angles thereto as at 2 and thence turned backwardly upon itself and cut out as at 3^a to form loops 3 and a plate 4. Plate 4 is continued past the plane of leaf 1 as shown whereby it may be secured to the edge of a door casing as 5. The inner edge of plate 4 is extended in part to form an ear 6 having an orifice 7 therein.

35 The second leaf of the hinge is shown at 8 and is attachable to the side of the door reverse to the side of the casing to which leaf 1 is attached and is provided with an ear 9 provided with an orifice 10. Leaf 8 is bent outwardly at substantially right angles to form plate 11 which is provided with terminal loops 12, alternating with loops 3, the loops 12 and 3 being in alignment and engaging a pin 13.

45 At 14 is shown a coiled spring attached to ears 6 and 9 through orifices 7 and 10 whereby to normally hold plates 4 and 11 in parallel relation to each other and thence to hold door 15 in closed position with relation to frame 16.

50 When the hinge is constructed as described and mounted upon a door and casing as indicated, the opening of the door 15 causes the spring 14 to assume a position such as

shown in dotted lines at 17. To prevent 55 interference with the action of spring 14 and also to prevent undue wear upon either the spring or hinge corner, a recess 18 is formed in the corner of leaf 8 at the point where the spring contacts upon opening the door. 60

It may now readily be seen that the hinge herein disclosed is easily made and of few parts since there are but four pieces namely, the two leaves, the spring and the pin. The construction of the hinge is such that the 65 cutting and bending of each leaf is a simple operation as also is the assembling of the leaves, pin and spring.

The spring is so arranged that its action is positive and powerful, yet can be removed 70 and replaced in a moment's time. Since no special design is required an old spring may be readily replaced at little cost and with little delay.

The formation of the recess 18 is important inasmuch as it renders the device practical with but small projections or ears on the leaves.

It is to be understood, of course, that while I have herein shown and described the particular embodiment of my invention desired, that changes in form, proportion, construction and method of operation may be made within the scope of the appended claim.

It is to be further understood that I do 85 not wish to confine myself to a form of hinge in which the spring 14 is used as the hinge without the spring may be useful in many applications.

I claim:—

A hinge comprising an element having two leaves arranged at right angles to each other for attachment to a door casing, one of said leaves having an ear extending outwardly therefrom, and a second element having leaves arranged at right angles to each other for attachment to a door, one of said leaves having an ear extending outwardly therefrom, a spring connecting said first and said last mentioned ears, and means for pivotally connecting said elements at a point remote from said ears, said ears being arranged to normally maintain said spring in parallel relation to the door and frame upon which it is mounted, but engaging one element when the door is opened.

BURT M. MOORE.
